UNITED STATES PATENT OFFICE.

AAGE HALFDAN JÖRGENSEN, OF LYNGBY, NEAR COPENHAGEN, DENMARK.

ALARM APPARATUS.

1,391,684.

Specification of Letters Patent. Patented Sept. 27, 1921.

Application filed April 11, 1919. Serial No. 289,398.

To all whom it may concern:

Be it known that I, AAGE HALFDAN JÖRGENSEN, a subject of the King of Denmark, residing at Lyngby, near Copenhagen, in the 5 Kingdom of Denmark, have invented certain new and useful Improvements in Alarm Apparatus, of which the following is a specification.

The present invention refers to an alarm 10 apparatus in case of burglary, fire, and the like, being devised for use in connection with previously installed telephone lines, so that the apparatus, in case of alarm, rings up the central telephone exchange, where, after 15 investigating the nature of the signal, the operator informs the police, fire-department, or the like, according to circumstances. Thus this alarm apparatus only requires a local installation of wires to the requisite 20 contact-members in the room or rooms, or the like, to be protected, and it is furnished with members which, in case of either ordinary closing of contact or injury to the wiring, *e. g.* the cutting of the wires, cause 25 the release of a mechanical force which as in telephone apparatus, opens or closes a ringing-current.

One form of construction of this device 30 applied in connection with a telephone installation with magneto-telephones, is diagrammatically shown on the drawing, which is a side-view of the apparatus, with part of the outer wiring.

In a suitable case there is disposed a set 35 of horseshoe magnets *a* with armature *b*, which is secured to a shaft *c* supplied with a hand-crank. To the shaft *c* is secured one end of a spiral spring *d*, the other end of which is held fast to the supporting frame 40 of the shaft by means of a nut *f*. The shaft *c* carries a wheel *e* with a notch *g* in its periphery, into which notch enters the hook-shaped arm *h* on a three-armed lever, when the spring *d* is wound, the hook *h* normally 45 preventing the shaft *c* from turning under the influence of the spring. A second arm *j* of the said lever which is pivoted at *i* carries an armature for an electro-magnet *k*, which, when active, attracts the armature, 50 so that the arm *h* is disengaged from the notch *g*.

Above the third arm *m* of the said lever there is disposed a one-armed lever *o* turnable on a pin *n* in a standard *q*, said lever 55 being actuated by a helical spring *p* fastened to the standard, which spring tends to move

the lever *o* down toward the arm *m*. The lever is normally held in position above the arm *m* as shown by means of a rod *r*, of insulating material, which carries a hook *s*, 60 which extends up through a suitable opening in a safety-plug *u* and grips around the filament fuse *t* disposed in this safety-plug, which is held fast in the standard *q*.

The winding of the electro-magnet *k* is, 65 by means of a conductor *1*, connected with one pole of an electric current source *v*, which, *e. g.*, may be the battery used for the telephone apparatus, the other pole of the battery being connected with a conductor *2* 70 which, over a terminal *3*, is carried out into the room or rooms to be protected and is here connected with one of the two parts of the contact members *w*, which are, *e. g.*, placed in doors, windows, money-safes, and 75 the like, or on the ceiling (to close the current in case of fire). The other end of the winding of the electro-magnet is, by means of a conductor *4*, through a terminal *5*, connected with the other part of the contact 80 members *w*, so that the current through the electro-magnet *k* from the battery *v* is closed whenever one of the contact members *w* is closed. This results in the armature attracting 85 the lever-arm *j*, so that the shaft *c*, actuated by the spring *d*, will turn. The current induced into the armature by the turning of the armature *b* is carried through conductors *10* and *11*, respectively connected with the shaft *c* and with a terminal *y*, which, 90 in turn, by means of a drag-spring, in a well known manner, are conductively connected with the armature, to the telephone conductors. In the conductor *10*, there is inserted 95 a switch *x*, so that the alarm apparatus can be thrown into and out of action when desirable.

In order to prevent the alarm apparatus 100 from being put out of action by cutting the conductors *2* and *4*, whereby the contact members *w* can be closed without current passing through the electro-magnet *k*, two high-voltage conductors, *9* and *7* respectively, are run parallel to the conductors *2* and *4*, *e. g.* from a light-contact *8* and *6*. The conductor *9* is 105 connected with the two ends of the fuse *t*, so that the latter is included in the circuit of the high-voltage current. Now when the main which supplies all the conductors *2*, *4*, *7* and *9* is cut, not only the conductors *2* and *4* are short-circuited, which will not always 110 be sufficient to set the electro-magnet *k* into

action, but also the high-voltage conductors 7 and 9, causing the fuse *t* to be melted. Thereby the hook *s* and the lever *o* are released, the latter, under the influence of the 5 spring *p*, striking down against the lever-arm *m*, so that the arm *h* is removed from the notch *g*, and the wheel *e*, on the shaft *c*, is released. Thus the alarm apparatus will, 10 in all cases, be sure to act when the switch *x* is closed.

I claim—

1. Alarm apparatus adapted to be inserted in the wiring of a telephone installation, comprising in combination with a local electric circuit, a movable member for producing an electric current causing the alarm, a means tending to operate said member, a locking means normally holding said member in inoperative position, a plurality of contact elements in said electric circuit, adapted to be automatically closed, a second electric circuit adapted to be short-circuited upon the cutting of the wires in the said first circuit, and means independent of each other 15 included in each circuit and adapted to disengage the said locking means releasing the said movable member upon any of the said circuits being closed.

2. An alarm apparatus comprising in combination with a local electric circuit, a movable member adapted to produce an electric current for causing the alarm, a spring tending to operate said member, a locking means normally holding said member in inoperative position, a plurality of contact members 30 in said electric circuit, adapted to be automatically closed, an electromagnet arranged in said circuit to disengage the said locking means upon the said electromagnet being energized by the closing of any of the said contact members, a second high-voltage circuit adapted to be short-circuited upon the cutting of the wires in the said other circuit, a fuse in said high-voltage circuit, a spring-controlled lever adapted to disengage said locking means, but normally held in inoperative position by said fuse, the latter upon the said high-voltage circuit being short-circuited being melted thereby releasing the said lever to disengage the said locking means. 35 40 45 50

In testimony whereof I affix my signature in the presence of two witnesses.

AAGE HALFDAN JÖRGENSEN.
